(57) **CLAIM**

We claim the or mental design for a washing machine, as shown and described.

DESCRIPTION

FIG. 1 is a perspective view of a washing machine showing our new design with its detergent dispenses fully pulled out;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view thereof with its detergent dispenser closed fully pushed in;

FIG. 9 is a front elevation view thereof;

FIG. 10 is a left-side elevation view thereof; and,

FIG. 11 is a top plan view thereof.

The broken lines in the drawing figures are included for the purpose of illustrating environment and form no part of the claimed design.
